CONTROL KNOB CLUSTER FOR A TV RECEIVER OR THE LIKE

Thomas E. Duvall, 7545 Lyons, Morton Grove, and Harry Ehrensaft, 7426 Kenneth Ave., Skokie, Ill.

Filed Nov. 12, 1958, Ser. No. 773,447

4 Claims. (Cl. 74—10.8)

Our invention relates to an improved control knob cluster for a TV receiver or the like which is adapted to operate a plurality of control mechanisms independent of each other and which presents an attractive appearance outside the TV cabinet.

The control knob cluster provided in accordance with the present invention includes a main knob, an intermediate plate and an indicating panel. The latter two elements are detachably mounted within the confines of the main knob by means of bolts which originate from a mounting plate located within the TV cabinet. A decorative skirt around the main knob presents an attractive appearance outside the cabinet.

The main knob has gear teeth around that part of its periphery located within the cabinet that mesh with a coarse tuning gear train which operates a station selector in coarse tuning operation. A fine tuning gear train mounted coaxially with respect to the coarse tuning gear train is driven by a fine tuning knob which is mounted within the confines of the main knob. A number of other auxiliary control knobs are similarly situated and operate their respective control mechanisms independently of each other.

The intermediate plate and indicating panel are so mounted in the main knob that the main knob rotates around them without interfering with the operation of the auxiliary control knobs. Also, the main knob may be easily separated from the TV cabinet by removing the indicating panel.

It is therefore a general object of the present invention to provide an improved control knob cluster for a TV receiver or the like which is adapted to operate a plurality of control mechanisms independently of each other.

It is another object of the present invention to provide an improved control knob cluster for a TV receiver or the like which presents an attractive appearance outside the TV cabinet without a trim plate.

It is a further object of the present invention to provide an improved control knob cluster for a TV receiver or the like having a plurality of auxiliary control knobs located within the confines of the main knob.

It is still another object of the present invention to provide an improved control knob cluster for a TV receiver or the like that is pleasing and attractive in appearance, inexpensive to manufacture, reliable in operation, easily assembled and disassembled, and compact in volume.

The novel features which we believe to be characteristic of our invention are set forth with particularity in the appended claims. Our invention itself, however, together with the further objects and advantages thereof, will best be understood by reference to the following description taken in conjunction with the accompanying drawings in which:

Figure 1 is a fragmentary side elevational view with parts in cross-section of a control knob cluster made in accordance with the present invention;

2

Figure 2 is a front elevational view of the main knob of Figure 1;

Figure 3 is a cross-sectional view through axis 3—3, Figure 2;

5 Figure 4 is a front elevational view of the intermediate plate of Figure 1;

Figure 5 is a cross-sectional view through the axis 5—5, Figure 4;

10 Figure 6 is an enlarged front elevational view of the indicating panel of Figure 1;

Figure 7 is an enlarged view like Figure 1 but showing a modified form of the present invention; and

Figure 8 is a view in cross-section through axis 8—8, Figure 7, on a somewhat reduced scale.

15 There is shown generally at 10, Figure 1, a control knob cluster adapted to operate a plurality of control mechanisms in a TV receiver or the like and to form an attractive appearance outside the TV cabinet without a trim plate. The main knob 12 is received in part within

20 the cabinet 14 of the TV receiver as shown. This portion has external gear teeth which are in engagement with a coarse tuning gear train which operates a station selector 20 within the cabinet in coarse tuning operation. An auxiliary control mechanism located within the con-

25 fines of the main knob is a fine tuning knob 22 having a fine tuning gear train which operates the station selector 20 in fine tuning operation. The gear trains are mounted coaxially with respect to one another so that they are operable independently of each other.

30 The control knob cluster 10 may also house a number of other auxiliary control mechanisms, such as a vertical hold knob 28, which operate and control various circuits within the TV receiver by means of potentiometers or other adjustable devices.

35 Referring now to Figures 1, 2 and 3, main knob 12 is of cylindrical conformation and has a portion 11 which is located outside the TV cabinet 14 and a portion 13 which is located within TV cabinet 14. Outside portion 11 is provided with a decorative skirt 32 which extends around the periphery of the knob. As can best be seen in Figure 1, skirt 32 extends up to and in closely spaced relation to TV cabinet 14, thereby effectively hiding the opening in the cabinet into which the control knob cluster is inserted and also provides an attractive and pleasing appearance outside the cabinet.

40 The main knob 12 has an internal outboard facing shoulder 34 in close proximity to outer portion 11. The knob 12 also has an internal inboard facing shoulder 36 which is of lesser diameter than outboard facing shoulder 34 and in close proximity to inner portion 13 of knob 12. Inner portion 13 is provided with teeth 16 of limited axial extent which operate, through a coarse tuning driven gear 18, the station selector 20 in coarse tuning operation, as will be discussed in more detail hereinafter.

45 55 A plurality of auxiliary control mechanisms are located within the confines of the main knob 12. All of these mechanisms are partially mounted within the knob 12 by means of an intermediate plate 38 and a detachable indicating panel 40. Referring now to Figures 1 and 6, the indicating panel 40 is of circular conformation and fits adjacent the outboard facing shoulder 34 of main knob 12. A number of sizable holes 42 have been cut in indicating panel 40 to receive auxiliary control knobs (such as knobs 22 and 28 as shown in Figure

50 1) which control, amongst other things, brightness, fine tuning, vertical hold, contrast, and turning the TV receiver on and off. The indicating panel 40 is also provided with a number of mounting holes 44, the purpose of which will be described in more detail hereinafter.

55 70 Referring now to Figures 1, 4, and 5, the intermediate plate 38, which also is of circular conformation but of

lesser diameter than the indicating panel 40, is fitted adjacent the inboard facing shoulder 36 of main knob 12. Plate 38 is provided with a plurality of bosses 46 which extend toward outer portion 11 of knob 12 and corresponding bosses 48 which extend toward inner portion 13 of main knob 12. The bosses 46 and 48 have centrally disposed holes 50 and 52, respectively, the purpose of which will be described in more detail hereinafter. Indicating plate 38 is also provided with a plurality of sizable holes 54 which are coextensive with the holes 42 on indicating plate 40 and which serve to receive a portion of the auxiliary control mechanisms, as will be described in more detail hereinafter.

It will be noted that the main knob 12 is in no manner affixed to the indicating panel 40 or the intermediate plate 38, but is merely rotatable about these units and is held in place by the shoulders 36 and 34.

As seen in Figure 1, the TV receiver chassis 56 has a panel 58 extending from the vertical rear chassis plate 60 forwardly to the region of knob 10. A station selector 20 of the kind that is normally used with standard TV circuits is mounted on chassis plate 60. Bosses 48 of intermediate plate 38 have their ends adjacent the panel 58 and are attached thereto by means of screws 66 which are threadedly received in the holes 52. Bosses 46 have their ends adjacent to indicating or cover plate 40 and also are affixed thereto by screws 68 threadedly received in holes 50. Thus it can be seen from Figure 1 that the indicating or cover plate 40 and the intermediate plate 38 serve to lock the main knob 12 against any longitudinal movement and, if indicating plate 40 is removed from bosses 46, the main knob 12 may be removed from the cabinet 14 without in any manner affecting the operation of the other components of the control knob cluster 10.

The panel 58 also serves as a mount for the fine tuning drive gear 24 which is operated by fine tuning knob 22. The drive gear 24 is in engagement with the fine tuning driven gear 26 which operates the station selector 20 in fine tuning operation. Teeth 16 on main knob 12 are in engagement with coarse tuning driven gear 18 which operates the station selector 20 in coarse tuning operation. It will be noted that both driven gears 18 and 26 are mounted coaxially with respect to one another, on the shaft 70a of the tuner 20. Fine tuning driven gear 26 is mounted on collar 70, which is received and supported in part by panel 58 and at portion 70b, extends into the tuner to operate the fine tuning mechanism of the same. Coarse tuning driven gear 18 is mounted on shaft 70a which extends through vertical plate 58 and shaft 70.

Chassis 56 serves as the sole support for the entire control knob cluster 10 and its associated parts. A number of auxiliary control mechanisms are located within the confines of the main knob 12. One of these is the fine tuning auxiliary mechanism which already has been described in detail. Another may be a vertical hold auxiliary mechanism which operates and controls the vertical hold circuit within the TV receiver. As best seen in Figures 1 and 6, this unit comprises a vertical hold knob 28, which is received through the vertical hold hole 42 of indicating panel 40. Knob 28 is also mounted on potentiometer or adjustable resistor 30 which is received in corresponding vertical hold hole 54 in intermediate plate 38, as shown in Figures 1, 4, and 5. Potentiometer 30 is electrically connected to the TV circuitry which controls the vertical hold circuit. It will be noted that the potentiometer 30 is located between the intermediate plate 38 and the vertical plate 58, thereby restricting and confining the control knob cluster to a minimum volume.

Other such auxiliary control mechanisms may be located in much the same manner as described with respect to the vertical hold auxiliary control mechanism. As seen in Figure 6, a number of holes have been provided in indicating panel 40 which are designed to receive knobs

which control, among other things, turning the TV receiver on and off, contrast, and brightness of the picture tube.

In the views of Figures 7 and 8, an alternative form of the present invention is shown. Similar parts are given the same reference numerals as those of the structure of Figures 1 to 6, with 100 added.

In the view of Figure 7, the TV receiver cabinet is indicated at 114 and has a suitable circular opening to receive the main knob 112. This knob is of essentially the same construction as that of Figure 1. In brief, it includes the skirt 132 which overlays the opening in the cabinet 114, the outwardly facing annular shoulder 134, the inwardly facing annular shoulder 136, and the spur gear teeth 116. The inner annular shoulder 136 of the knob 112 seats against the intermediate plate 138 which is supported from the receiver chassis by the posts 148 which correspond to the bosses 48, Figure 1. The forwardly facing annular shoulder 134 of the knob 112 seats against the indicating panel 140d which is held by screws 168 through the forwardly projecting arms 146 which are affixed to the plate 138. The knob 112 thus held in position in the same fashion as is the knob 12, Figure 1.

The receiver controls 128 project through suitable openings in the plate 140, as shown in Figure 7. In the case of some of these controls, such as the on-off and volume control 129, the controlled elements (in this instance the potentiometer and switch) are mounted directly on plate 138. To accommodate such controls, the vertical plate 166 of the chassis is apertured at 167. Also in order to provide ample room for such controls the shaft 125 which carries the fine tuning gear 124 is of somewhat increased length as compared to the arrangement of Figure 1.

In order to provide ample support for the shaft 125 it is provided with a headed extension 125a which is received in the socket 169a of the angle bracket 169 which is held at its toe portion 169b to the vertical plate 166 by the screw 171. The knob 112 drives the channel selector drive gear 118 in the same fashion as the structure of Figure 1. The fine tuning gear 124 drives the fine tuning gear 126 of the tuner 120 by reason of their meshing engagement.

In addition to the control 129 which is mounted on the panel 138, other controls such as 131 and 133 may be mounted on the panel 166. Since the gear 124 is located some distance to the rear of panel 166 in the form of the unit of Figures 7 and 8, there is ample clearance and no interference takes place.

As constructed, the control knob cluster, consisting of the main knob 12 (112, Figures 7 and 8) and a plurality of auxiliary control mechanisms located within the confines of the control knob, are operable independently of each other and one another. They provide a highly effective control unit for a TV receiver or the like, while at the same time presenting an attractive appearance outside the cabinet of the TV receiver and permitting convenient removal of the chassis from the cabinet when desired.

While we have described and shown a specific embodiment of the present invention it will, of course, be understood that various modifications and alternative constructions may be made without departing from the true spirit and scope thereof. We therefore intend by the appended claims to cover all such modifications and alternative constructions falling within their true spirit and scope.

What we claim as new and desire to secure by Letters Patent of the United States is:

1. A control knob cluster for a TV receiver or the like and adapted to operate a station selector in coarse and fine tuning operation and to form an attractive appearance outside the cabinet without a trim plate comprising in combination: a mounting panel; coarse tuning and fine tuning coaxial driven gears on said panel adapted to

operate the station selector in coarse and fine tuning operation respectively; a main tuning knob of cylindrical conformation having teeth of limited axial extent in engagement with the coarse tuning driven gear, said knob extending outside the cabinet and having a decorative skirt outboard the cabinet and extending to closely spaced relation therewith, the knob further having an internal outboard facing shoulder and an internal inboard facing shoulder of less diameter than the outboard facing shoulder; an intermediate plate affixed to the panel and protruding outboard the same within the confines of the knob and adjacent the inboard facing shoulder thereof; an indicating panel removably secured outboard the intermediate plate and overlaying the external outboard shoulder of the knob; and a fine tuning knob with a drive gear in mesh with the fine tuning driven gear located within the confines of said main knob.

2. A control knob cluster for a TV receiver or the like and adapted to operate a station selector in coarse and fine tuning operation and to present an attractive appearance outside the cabinet without a trim plate comprising in combination: a mounting panel on said cabinet having a horizontal plate on which said selector is received and a vertical plate; coarse tuning and fine tuning coaxial driven gears adapted to operate the station selector in coarse tuning and fine tuning operation; a main tuning knob of cylindrical conformation having teeth of limited axial extent in engagement with the coarse tuning driven gear, said knob extending outside the cabinet and having a decorative skirt outboard the cabinet and extending to closely spaced relation therewith, the knob further having an internal outboard facing shoulder and an internal inboard facing shoulder of lesser diameter and in closer proximity to said vertical panel than the outboard facing shoulder; an intermediate plate outboard of and affixed to the vertical panel within the confines of the knob and adjacent the inboard facing shoulder thereof, whereby said intermediate plate and indicating panel serve to lock the knob against longitudinal movement and as shafts around which the knob rotates; a fine tuning knob on said indicating panel with a drive gear on said vertical plate in mesh with the fine tuning driven gear, said control mechanism located within the confines of said main knob; and a plurality of auxiliary control mechanisms, each having a knob and control mechanism located within the confines of said main knob and a control mechanism on said indicating panel and a control mechanism on said intermediate plate.

3. A control knob cluster for a TV receiver or the like and adapted to present an attractive appearance outside

the cabinet without a trim plate comprising in combination: a mounting panel on the cabinet; a main knob of cylindrical conformation extending outside the cabinet and having a decorative skirt outboard the cabinet in closely spaced relation therewith, the main knob further having an internal outboard facing shoulder and an internal inboard facing shoulder of lesser diameter and in closer proximity to said mounting panel than the outboard facing shoulder; an intermediate plate outboard of and affixed to the mounting panel within the confines of said main knob and adjacent the inboard facing shoulder thereof; an indicating panel outboard of and removably secured to said intermediate plate within the confines of said main knob and adjacent the outboard facing shoulder, whereby said intermediate plate and indicating panel serve to lock the main knob against longitudinal movement and as shafts around which the knob rotates; a plurality of auxiliary control mechanisms, each having a knob and control mechanism located within the confines of said main knob whereby the main knob and the other knobs are operable independently of each other.

4. A control knob cluster for a TV receiver or the like and adapted to present an attractive appearance outside the cabinet without a trim plate comprising in combination: a mounting panel on said cabinet; a main knob of cylindrical conformation extending outside the cabinet having a decorative skirt outboard the cabinet in closely spaced relation therewith and having an internal outboard facing shoulder and an internal inboard facing shoulder of lesser diameter and in closer proximity to said mounting panel than the outboard facing shoulder; an intermediate plate outboard of and affixed to the mounting panel within the confines of said main knob and adjacent the inboard facing shoulder thereof; an indicating panel outboard of and removably secured to said intermediate plate within the confines of said main knob and adjacent the outboard facing shoulder; and a plurality of auxiliary control mechanisms each having a knob and control mechanism partially mounted on said indicating panel and each operable independently of each other and said main knob, whereby detaching the indicating panel allows removal of the main knob without affecting operation of the auxiliary control mechanisms.
